[57] CLAIM

The ornamental design for a valve, as shown and described.

DESCRIPTION

FIG. 1 is a right side elevational view of a valve showing our new design, the left side being a mirror image of the right side;

FIG. 2 is a perspective view taken from the top, front and right side thereof;

FIG. 3 is another perspective view taken from the top, rear and left side thereof;

FIG. 4 is a third perspective view taken from the bottom, rear and right side thereof;

FIG. 5 is a top, front perspective view of the valve body thereof;

FIG. 6 is a top, rear perspective view of FIG. 5; and, FIG. 7 is a bottom perspective view of the valve actuator thereof.

Related U.S. Application Data

[63] Continuation of Ser. No. 921,201, Oct. 21, 1986, abandoned.
